United States Patent Office

Des. 219,874
Patented Feb. 9, 1971

219,874

BATHTUB

Jack A. Goodall, Dallas, Tex., assignor to Venetian Marble Company, Dallas, Tex., a corporation of Texas

Filed July 12, 1968, Ser. No. 12,722

Term of patent 14 years

Int. Cl. D23—02

U.S. Cl. D23—55

FIG. 1

FIG. 2

FIG. 3

FIG. 4

FIG. 1 is a top plan view of a bathtub showing my new design;

FIG. 2 is a side elevational view thereof;

FIG. 3 is a cross sectional view taken on line 3—3 of FIG. 1; and

FIG. 4 is a cross sectional view taken on line 4—4 of FIG. 1.

I claim:

The ornamental design for a bathtub, as shown.

UNITED STATES PATENT OFFICE
CERTIFICATE OF CORRECTION

Patent No. Design No. 219,874 Dated February 9, 1971

Inventor(s) Jack A. Goodall

It is certified that error appears in the above-identified patent and that said Letters Patent are hereby corrected as shown below:

In the heading to the drawings and printed specification, lines 3 and 4, "Venetian Marble Company, Dallas, Tex., a corporation of Texas" should read -- Venetian International, Inc., Dallas, Tex., a corporation of Texas --.

Signed and sealed this 20th day of July 1971.

(SEAL)
